UNITED STATES PATENT OFFICE.

SIEGMUND LOEWE, OF BERLIN, GERMANY, ASSIGNOR TO WESTINGHOUSE ELECTRIC & MANUFACTURING COMPANY, A CORPORATION OF PENNSYLVANIA.

EQUIPMENT FOR WIRELESS RECEIVING OR TRANSMITTING APPARATUS.

Application filed August 26, 1921, Serial No. 485,783, and in Germany December 30, 1915.

(GRANTED UNDER THE PROVISIONS OF THE ACT OF MARCH 3, 1921, 41 STAT. L., 1813.)

My present invention relates to the practical construction of receiving or transmitting apparatus for wireless stations. Wireless receiving apparatus generally contains 5 rather complicated connections, so that anyone opening the apparatus must take considerable trouble to trace out such connections. To facilitate this work various colours have been applied to the various circuits, for example, the conductors of the antenna circuit have been coloured green, those of the secondary circuit red and so on.

My present invention discloses a new procedure. To exemplify this, the apparatus 15 appertaining to the secondary circuit, such as coils, condensers and switches, when required, would be combined into one independent whole, likewise all parts of the aperiodic circuit by themselves, likewise all 20 parts appertaining to the antenna circuit by themselves, and finally all parts appertaining to a separate test device, if present, by themselves.

An embodiment of my invention is illustrated by way of example in the accompanying drawing, wherein Fig. 1 is a perspective view showing an assembly of the independent apparatus elements.

Fig. 2 is a perspective view of a modified 30 embodiment of my invention.

Fig. 3 is still another modification.

Referring to Fig. 1 the antenna coil 1 and the antenna connection 2 are mounted in a box 10, the secondary coil and accessories 35 in a box 11, the telephone 4 and detector 5 in a box 12, the test circuit 6 in a box 13 and the tertiary circuit in a box 14. The boxes 10 and 14 can if desired be placed alongside one another.

40 Broadly speaking, a receiving equipment according to the present invention consists of a succession or series of independent apparatus-elements, which can be manufactured singly, which permit of independent 45 testing, and which may be exchanged as desired for other apparatus-elements either similar or of a different kind. They are parts complete in themselves, which enter into electrical relation with one another only 50 by special proximity. An arrangement of this kind is shown diagrammatically in the drawing.

What can be obtained in the way of novel

effects may be shown by the example. Here 55 the associated parts of the antenna circuit are mounted in a box, likewise the associated parts for the aperiodic circuit. If the two boxes are simply placed alongside one another the usual primary receiving is effected. If the boxes are shifted apart and 60 there is placed between them a box containing the parts of the secondary circuit, secondary receiving is effected. If it is desired to effect tertiary receiving, one simply places 65 in between them a box containing the tertiary circuit.

The improvement obtained can be here 70 only indicated. In addition to the great ease of inspection there is the most important advantage that it is possible to adapt the receiving apparatus to suit the immediate occasion. It is possible to select from the various receiving methods that which is the most advantageous in a particular case. For 75 example should the operator when receiving be suddenly seriously disturbed with a long wave, he can interpolate a secondary circuit for receiving the desired wave through the combination of a very large self induction with a very small condenser. Hereby the long wave is weakened to a far greater extent than the wave being received. If a disturbance from a very short wave suddenly arises, the operator, if he has placed, beside 80 and somewhat to the right of the antenna box, the secondary circuit and aperiodic circuit, would place to the left and alongside the antenna box another secondary box, which he tunes to a very short wave, whereby 85 it is brought about that energy of the disturbing wave is branched off toward the latter box and there dissipated. The above 90 embodiments of the invention are only explanatory examples intended to show what novel effects can be brought about by the invention. To what an extensive degree the proposed receiver construction may be employed will be understood from the fact that, 95 for example, the chief of a military station has it in his power to adapt the wireless receiving apparatus of his station to the capacities of his staff of operators. If his staff is capable of being trusted with the apparatus he will place at their disposal the box for secondary receiving. If on the other 100 hand he has to deal with an untrained per-

sonnel, he will limit himself to permitting primary receiving and will lock up everything not appertaining thereto. It need here only be mentioned that one of the errors most 5 to be feared, in particular with apparatus fitted out for primary and secondary receiving, is that the staff, when exploring, should allow the secondary circuit to be connected in owing to ignorance of the fact that this 10 circuit by its selective action lets through only a strictly predetermined wave. In such cases the chief of the station gives to the staff the most stringent orders, but usually in vain, the call remains unheard. The receiving apparatus according to the present 15 invention enables the station chief completely to remove that which may be a source of error.

The above description is of course, not to be taken so literally that in reality each apparatus-element must be mounted by itself in a separate box, it rather suffices by the nature of the present invention that the individual circuits are separately combined with one another, while it is immaterial whether for this purpose the secondary circuit is mounted in a box or on a removable plate, or is set in an insertable frame. No one will obviously carry the principle to in-expediency by, for example, carrying the sub-division so far that, for the production of comparatively simple arrangements, the frequent connecting together of small single elements is necessary. The constructional sub-division would rather conveniently end where such is justified for electrical reasons, for example, to suit each closed circuit. Thereby the very economical advantage is obtained that one can deal with other electrical dimensioning such as becomes necessary, for example, when employing two different sized antennæ on one station, only one other box being inserted for the other antenna while for everything else, the secondary and aperiodic circuits, may be retained.

50 Those versed in the art will be able to easily decide upon the most desirable arrangement of the apparatus-elements or parts separable from one another in such manner that when the elements are brought into juxtaposition with one another they will enter into the correct electrical relation so that those elements, e. g. the coils, which 55 are intended to execute an inductive transfer one to another, are correctly placed relatively to one another when the apparatus-elements are brought into proximity or combined. Separability does not exclude the 60 contingency that when combination occurs, parts of one apparatus engage into those of the other e. g., contacts of adjusting devices into one another. These are requirements constructively easy to be fulfilled.

Figure 2 shows a modified embodiment of my invention in which the operating keys 8 for the transmitting apparatus and keys 9 of the receiving apparatus are arranged on two different walls of the casing perpendicular one to the other. According to Figure 3 the keys are arranged on different parts of the horizontal and the vertical wall of the casing respectively. Further the upper plate 15 at the right hand of Figure 3 is enabled to be opened so as to be used as a table for writing purposes.

Having now particularly described and ascertained the nature of my said invention and in what manner the same is to be performed I declare that what I claim is:

1. The combination in high frequency signaling equipment of a plurality of individually separable self-contained units each comprising a closed circuit and radio apparatus associated therewith, said units being capable of operating conjointly for signaling purposes when placed in proper mutual space relation. 85

2. The combination in high frequency signaling equipment of a plurality of individually separable self-contained units each comprising a box containing a closed circuit and the radio apparatus associated therewith, said units being capable of operating conjointly for signaling purposes when placed in proper mutual space relation. 90 95

3. The combination in high frequency signaling equipment of a plurality of individually separable self-contained units each comprising a box containing one or more closed circuits and the radio apparatus associated therewith, all of said units being capable of operating conjointly and others of said units being capable of operating in conjunction with one or more of the others of said units independently of certain other or others of said units. 100 105

4. In a radio system, a plurality of different circuits, means associated with the respective circuits for performing the usual radio operations, and consolidating structures securing each circuit and its associated means together to form a unit, whereby the several units may be separately moved, each as a whole, to enable any selected units to be brought into cooperative relation. 110 115

5. In a radio system, a plurality of stages, each stage including the means for performing one step in the transformation of signals, consolidating structures constituting each of said stages into a unit, whereby the several units can be separately moved, each as a whole, and thereby any predetermined combination of stages may be properly positioned for cooperative action. 125

In testimony whereof I affix my signature.

DR. SIEGMUND LOEWE.
